(57) **CLAIM**

The ornamental design for a single serve coffee maker as shown and described.

DESCRIPTION

FIG. 1 is a left front perspective view of a single serve coffee maker.

FIG. 2 is a front view of the single serve coffee maker of FIG. 1.

FIG. 3 is a rear view of the single serve coffee maker of FIG. 1.

FIG. 4 is a right-side view of the single serve coffee maker of FIG. 1.

FIG. 5 is a left-side view of the single serve coffee maker of FIG. 1.

FIG. 6 is a top view of the single serve coffee maker of FIG. 1; and,

FIG. 7 is bottom view of the single serve coffee maker of FIG. 1.

The broken lines in the figure drawings illustrate portions of the single serve coffee maker that form no part of the claimed design.

1 Claim, 7 Drawing Sheets
